JOHN V. BREISKY, OF PITTSBURGH, PENNSYLVANIA, ASSIGNOR TO WESTINGHOUSE ELECTRIC & MANUFACTURING COMPANY, A CORPORATION OF PENNSYLVANIA

DIRECT-CURRENT RELAY

Application filed August 25, 1925, Serial No. 52,454. Renewed September 11, 1929.

My invention relates to relays and particularly to direct-current relays.

One object of my invention is to provide an improved differential relay.

5 Another object of my invention is to provide a sensitive differential relay having an adjustable operating-time characteristic.

10 Another object of my invention is to provide a relay having a field-magnet structure comprising a polarized magnet, soft-iron pole pieces secured to said magnet and differential windings on said pole pieces for controlling an armature member.

15 Other objects and advantages of my invention will appear from the following detailed description of a relay constructed in accordance therewith.

In the accompanying drawings,

20 Figure 1 is a plan view of a relay embodying the invention, parts of the casing and the frame being broken away in order to show the construction of the armature member and field magnet more clearly.

Fig. 2 is a front view of the relay shown 25 in Fig. 1.

Fig. 3 is a side view, partially in section, of the relay shown in Figs. 1 and 2, and

30 Fig. 4 is a diagrammatic view of an automatic reclosing circuit-interrupter system employing the relay shown in Figs. 1 to 3.

The relay shown in the drawing comprises a frame member 1 upon which a vertical spindle or shaft 2 is pivoted in bearings 3 and 4. An armature member 5 and a disc member 35 6 are mounted upon the shaft 2. A field-magnet structure 7 co-operates with the armature member 5. A permanent magnet 8 co-operates with the disc member 6 to damp the movements thereof. The damping magnet 8 may be omitted if it is desired that the 40 relay shall have an instantaneous operating-time characteristic.

The armature member 5 comprises a magnetizable segment 10 of iron disposed eccentrically with respect to the shaft 2 in an aperture in a substantially circular disc member 11 of non-magnetizable metal. The thickness and configuration of the magnetizable armature member 10 depend upon the desired operating characteristics of the relay. 50

The thickness of the disc member 11 is preferably such that the weight per unit area is the same as that of the armature member 10. Since the armature member is mounted in an aperture in the disc member 11, and the two members are of equal weight per unit area, the composite armature member comprising the magnetizable and non-magnetizable portions 10 and 11 is balanced upon the shaft 2. Accordingly the bearings 3 and 4 55 60 may be delicate and substantially frictionless, and no error is introduced by an unbalance of the moving element.

As shown in Fig. 3, the upper bearing 3 may be of the pin type, because the lateral 65 thrust against the bearing is slight on account of the fact that the entire moving element, comprising the shaft 2 and the members supported thereon, is substantially balanced. The bearing comprises the pin 12 70 in the upper end of the shaft 2 engaging the stationary bearing member 13 on the frame. The lower bearing 4 comprises a steel ball 15 disposed between sapphire or other jewel bearings 16 and 17 on the shaft 75 and frame, respectively. The provision of a balanced moving element and frictionless bearings in the relay reduces the errors from friction or unbalanced masses.

The field-magnet structure 7 comprises a 80 polarized magnet 20 having soft-iron pole pieces 21 and 22 secured to the upper and lower ends thereof (see Figs. 1 and 3). The lower pole piece 22 is split into two parallel portions 23 and 24 on which are disposed 85 differentially-related windings 25 and 26. The tips of the lower pole piece are separated by a considerable air-gap as indicated at 27, (see Fig. 1) to reduce the leakage flux and to increase the torque on the armature member 5.

As shown in Figs. 3 and 4, the parallel portions 23 and 24 of the lower pole piece 22 terminate adjacent to the armature member 10 on the opposite side thereof from the upper pole piece 21. The winding 25 is wound in opposite directions upon the portions 23 and 24 of the split pole piece 22. The winding is shown on the drawing as comprising upper and lower sections, the reason for this 100

being shown on Fig. 3. The disc member 6 in the relay shown in the drawing separates the field winding into upper and lower sections, although this might be unnecessary if different proportions were used in the field structure and the moving element of the relay.

The winding 26 is also wound in opposite directions upon the portions 23 and 24 and is wound in such direction as to oppose the winding 25. In order to secure a more perfect balance between the two opposing windings, the winding 26 upon each portion of the split pole piece also comprises an upper and a lower section adjacent to, and concentric with, the sections of the winding 25.

The polarized magnet 20 polarizes the pole pieces 21 and 22 when the windings 25 and 26 are de-energized or are equally energized. The magnetic flux divides equally between the portions 23 and 24 of the split pole pieces 22 under these conditions. When one of the windings 25 or 26 is energized more strongly than the other, one of the parallel portions 23 or 24 of the split pole piece 22 is strengthened and the other is weakened depending upon which winding predominates. There is no tendency to de-magnetize the polarized magnet 20, the windings 25 and 26 operating simply to unbalance the distribution of the flux from the split pole piece 22.

A movable contact member 29 is secured to the spindle 2 and is adapted to co-operate with stationary contact members 30 and 31 depending upon the energization of the windings 25 and 26. Since no control spring is provided, when the relay is de-energized or the two differential windings are equally energized, the armature member 10 does not assume any definite position but remains in its initial position until the flux distribution between the upper and lower pole pieces 21 and 22 becomes unbalanced. If the energization of the windings 25 and 26 is such as to concentrate the flux upon the tip of the pole piece 23, the armature member 10 is attracted to the position shown in Fig. 1. If the conditions are reversed and the flux is concentrated upon the tip of the pole piece 24, the armature member 10 is attracted to a position corresponding to that shown in Fig. 1 adjacent to the pole tip 24. A control spring may be provided if desired to co-operate with the field magnet structure 7 for controlling the armature member 10 of the relay in certain applications thereof.

The fixed contact members 31 are supported on a pivoted arm 32 (see Figs. 1 and 2) which may be turned about the axis of the shaft 2. Adjustment of the arm 32 changes the spacing of the contact members 29 and 31 and thereby changes the operating time of the relay since the movement of the armature member is damped by the damping magnet 8. A scale 33 may be provided for

co-operation with the movable arm 32 to facilitate the timing adjustment of the relay and to indicate the time setting after the relay has been adjusted.

An important application of the relay described above is shown in Fig. 4 in which a direct-current distribution system, comprising a generator 35 and a load circuit 36, is provided with a circuit-interrupter 37 controlled by the contact members 29, 30 and 31 of the control relay.

In the system shown in Fig. 4, if a short-circuit occurs upon the load circuit 36, the circuit-interrupter 37 is opened through the instrumentality of an overload relay 38. The operation of relay 38 opens the holding circuit of the circuit-interrupter 37. The holding circuit of the interrupter may be traced from one conductor of the supply circuit through the normally closed contacts 39 of the transfer switch associated with the circuit-interrupter 37, the closing coil 40 of the circuit-interrupter and the contacts of relay 38 to the other side of the supply circuit.

When the circuit-interrupter 37 opens, a circuit is completed from the point 41 on one side of the circuit-interrupter 37 through the winding 25 of the control relay and a resistor 42 to the point 43 on the opposite side of the circuit-interrupter. If the short-circuit still exists upon the load circuit 36 or if any load is connected to this circuit, the winding 25 of the relay is traversed by a current which depends upon the magnitude of the resistance of the short-circuit or load on the load circuit 36.

The energization of the winding 25 actuates the armature member 10 to the control relay in such direction as to effect engagement of the movable contact member 29 with the back contacts 30, since the winding 26 of the relay is open-circuited. Upon the closure of the circuit including the contact members 30, a circuit is closed from one side of the supply circuit through the contact members 29 and 30, the winding of an auxiliary relay 44, the normally open contacts 45 of the transfer switch associated with the circuit-interrupter 37, the resistor 46 and the contact members of the overload relay 38 to the opposite side of the supply circuit. The auxiliary relay 44 becomes energized and closes a locking circuit for its own winding through its uppermost contact members that is independent of the contact members of the control relay.

The operation of relay 44 closes a circuit from the point 41 through its lowermost contact members and a resistor 47 to the point 43, thereby establishing a circuit in shunt to the contact members of the circuit-interrupter 37. A circuit is also closed from the point 41 through the winding 26 of the control relay, an adjusting resistor 48 and the second contact members of the auxiliary re-

lay 44 to the opposite side of the supply circuit. The winding 26 of the control relay is connected, therefore, across the generator 35.

5 The winding 25 of the control relay is energized directly in proportion to the current traversing the load circuit and, as long as the short-circuit exists, the current traversing the winding 25 is sufficient to maintain the contact member 29 of the control relay in engagement with the back contact members 30 of said relay. When the resistance of the load circuit increases to a predetermined value, the winding 26 predominates over the winding 25, and the movable contact member 29 is actuated into engagement with the front contact members 31 of the control relay.

10 Upon the engagement of the contact members 29 and 31, a circuit is closed from one side of the supply circuit through said contact members, the third contact members of the control relay 44, the closing coil 40 of the circuit-interrupter 37 and the contact members of the overload relay 38 to the opposite 15 side of the supply circuit. The closing coil 40 becomes energized and the circuit-interrupter 37 is reclosed.

20 The described automatic reclosing system recloses the interrupter 37 at a definite load resistance irrespective of variations in the voltage of the generator 35 since the windings 25 and 26 are both equally affected by variations in the supply voltage. Since the control relay does not embody a restraining 25 spring, the operation of the relay is exactly in accordance with the load resistance throughout the entire travel of the armature member. While the errors introduced by the use of a restraining spring may be reduced 30 by using a very light spring, the use of a delicate spring is not desirable. Furthermore, an appreciable error is always introduced by the use of a spring, whereas there is no theoretical error in the operation of the 35 relay shown in the drawing. The restoration of the movable contact member 29 to a retracted position before the control relay is operative to effect reclosure of the circuit-interrupter insures a definite time delay in 40 the reclosing of the interrupter after the load 45 resistance drops to normal.

50 I do not consider that my invention is limited to the details of construction shown and described herein, nor that the relay is limited to the specific application illustrated in Fig.

55 4. Accordingly, I do not desire to be limited in scope except as may be indicated in the appended claims.

60 5. I claim as my invention:—

65 1. A relay comprising a movable magnetizable armature member, a polarized field magnet having a split pole piece co-operating with said armature member and differentially-related windings on the respective por-

tions of said split pole piece for controlling the armature member.

70 2. A relay comprising a pivoted magnetizable armature member, a polarized field magnet having pole pieces on opposite sides of the armature member along the axis thereof and differentially-related windings on said field magnet for controlling the armature member.

75 3. A relay comprising a pivoted magnetizable armature member, a polarized field magnet having pole pieces on opposite sides of the armature member along the axis thereof, differentially-related windings on said field magnet for controlling the armature member 80 and means for damping the movements of said armature member.

85 4. A relay comprising a pivoted magnetizable armature member, a polarized field magnet having pole pieces on opposite sides of the armature member along the axis thereof, differentially-related windings on said field magnet for controlling the armature member and means whereby said armature member is restrained only in accordance with the rate 90 of movement thereof.

95 5. A relay comprising a vertical shaft, a magnetizable armature member supported thereby for movement in a horizontal plane, a polarized field magnet, upper and lower pole pieces secured to said field magnet and disposed above and below said armature member and differentially-related windings so disposed with respect to the field magnet structure as to control said armature member.

100 6. A relay comprising a vertical shaft, a magnetizable armature member supported thereby for movement in a horizontal plane, a polarized field magnet, a pole piece secured to one end of said field magnet and extending adjacent to said armature member, a split pole piece secured to the other end of said field magnet and disposed on the opposite side of said armature member and differentially-related windings on each element of said split pole piece for controlling said armature member.

115 7. A differential relay comprising a movable magnetizable armature member, a polarized field magnet therefor having a split soft-iron pole piece disposed adjacent to the armature member and differentially-related windings on each element of said split pole piece, each winding on one element being connected in series with a winding of opposite polarity 120 on the other element.

125 8. A differential relay comprising a magnetizable armature member, means for establishing parallel magnetic fluxes traversing said member and normally-balanced windings so arranged as to alter the relative strengths of said magnetic fluxes when the currents traversing said windings vary from a predetermined ratio.

130 9. A differential relay comprising a mag-

netizable armature member, means for establishing parallel magnetic fluxes traversing said member, normally-balanced windings so arranged as to alter the relative strengths of said magnetic fluxes when the currents traversing said windings vary from a predetermined ratio and means for introducing a time interval into the operation of the armature member in its movement in either direction.

10 In testimony whereof, I have hereunto subscribed my name this 7th day of August, 1925.

JOHN V. BREISKY.
